CLAIM

The ornamental design for a face plate for a video game controller, as shown and described.

DESCRIPTION

FIG. 1 is a top perspective view of a face plate for a video game controller embodying our new design, according to one embodiment;

FIG. 2 is a top view thereof;

FIG. 3 is a bottom view thereof;

FIG. 4 is a left side view thereof;

FIG. 5 is a right side view thereof;

FIG. 6 is a front view thereof; and

FIG. 7 is a rear view thereof.

FIG. 8 is a top perspective view of a face plate for a video game controller embodying our new design, according to another embodiment;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a rear view thereof.

The dashed lines shown in the figures depict portions of the face plate for a video game controller that form no part of the claimed design.
